[57] **CLAIM**

The ornamental design for a ball glove webbing, as shown and described.

DESCRIPTION

FIG. 1 is a perspective view of a ball glove webbing showing my new design, the conventional parts of the glove being shown in broken lines for illustrative purposes only and form no part of the claimed design;

FIG. 2 is a front elevation view thereof as viewed from a palm side of the glove;

FIG. 3 is a top plan view thereof;

FIG. 4 is a rear elevation view thereof;

FIG. 5 is a side elevation view thereof; and,

FIG. 6 is a bottom plan view thereof.
